UNITED STATES PATENT OFFICE.

HARRISON CADY, OF BROOKLYN, NEW YORK, ASSIGNOR TO THORNTON W. BURGESS, OF SPRINGFIELD, MASSACHUSETTS.

DESIGN FOR A GAME-BOARD OR SIMILAR ARTICLE.

50,235.

Specification for Design.

Patented Jan. 30, 1917.

Application filed May 6, 1916. Serial No. 95,975. Term of patent 3½ years.

To all whom it may concern:

Be it known that I, HARRISON CADY, a citizen of the United States, and resident of the borough of Brooklyn, county of Kings, city and State of New York, have invented a new, original, and ornamental Design for a Game-Board or Similar Article, of which the following is a specification, reference being had to the accompanying drawings, forming part thereof.

The figure is an elevation or front view of a game board, showing my new design therefor.

The design comprises a fanciful representation of a tree with various shaped openings.

I claim:

The ornamental design for a game board or similar article, as shown and described.

HARRISON CADY.
